UNITED STATES PATENT OFFICE.

ERWIN G. MUNZER, OF CHICAGO, ILLINOIS.

LADY'S UNDERGARMENT.

Application filed February 20, 1922. Serial No. 537,763.

To all whom it may concern:

Be it known that I, ERWIN G. MUNZER, a citizen of the United States, and a resident of Chicago, in the county of Cook and State 5 of Illinois, have invented certain new and useful Improvements in Ladies' Undergarments; and I do hereby declare that the following is a full, clear, and exact description thereof, reference being had to the accompanying drawings, and to the characters of 10 reference marked thereon, which form a part of this specification.

This invention relates to a novel under garment for ladies' wear in the nature of a 15 combined chemise and knicker, the upper part of the garment fitting loosely about the waist and the bust, and the lower part of the garment being shaped to fit loosely over the hips, and formed at its lower end to 20 produce short leg portions and above the crotch with a drop flap which is formed at its lower side as part of the material of the garment, and is free at its side and top margins to fit over and lap beyond a seat opening, and is detachably fastened at its top 25 margin to the rear side of the garment near its waist line.

The invention consists in the combination and arrangement of the parts shown in the 30 drawing and described in the specification, and is pointed out in the appended claims.

In the drawings:

Figure 1 is a rear view of a garment embodying my invention.

Figures 2 and 3 are plan views of the 35 front and rear portions of the garment.

Figure 4 is a plan view of one half portion of the drop seat flap and leg portion.

Figure 5 is a section on the line 5—5 of 40 Figure 1.

The garment 10 is made of four parts, one front portion 11, one rear portion 12, and two drop seat flap leg portions 13. The front and rear portions are similar in general 45 outline, comprising straight bust and back portions 14, 15, respectively, and outwardly curved or widened hip portions 16, 17, respectively. The front and rear portions, laid one on the other, are sewed together at their side margins along side 50 seams which extend from the top margins 18 to points indicated at 19 on the said front and rear portions, leaving the margins of the front and rear portions free below said 55 points 19 to form loosely open outer leg portions. The portions thus sewed together

produce a tubular, free fitting, shirt-like garment which can be suspended from the shoulders in any suitable manner. Straps 20 are herein shown for this purpose, although arm holes at the top of the garment will serve the same purpose.

The front portion 11 of the garment is cut at its lower margin to produce an inverted, V-shaped crotch notch 21. The rear portion 12 is centrally cut away from its lower margin upwardly to produce a deep wide notch 22. Said notch forms at the sides of said rear portion back leg portions 23, 23, and the upper part of said notch is sufficiently high to produce a seat opening 24, which is indicated in dotted outline in Figure 1 and full lines in Figure 3.

Each drop seat flap and leg part 13 comprises a lower rear leg portion 25 and an upper half seat flap portion 26. One straight, outer margin 27 of each seat flap part, at the lower end thereof, is short and is adapted to be stitched to the inner margin 22 of the appropriate rear leg portion 23. Above said short margin 27 each closing flap part is offset outwardly to produce a short, offset margin 29, from whence the remaining longer length 30 of the outer margin extends at a small, oblique, inward angle to the top margin 31. The other or inner margin of each said closing flap part comprises a longer, straight, oblique portion 32 and a shorter, lower, curved portion 33, which meets the lower curved margin of the leg portion of said closing flap part, as shown in Figure 4. The offset margins 29 are lapped over on the rear leg portions 23 and are stoutly stitched thereto. Said offset portions of the closing flap parts define the bottom or folding line of the closing flap when the two flap parts are stitched together along their margins 32, as most clearly indicated in Figure 1.

The manner of applying the closing flap 100 and leg parts 13 to the rear portion 12 is indicated by the dotted outline in Figure 3, wherein it will be noted that the margins 27 slightly overlap the margins 22 and are stitched thereto to constitute the rear inner leg portion of the garment, as best shown in Figure 1. The inner margins 32 of the drop flap parts are stitched together from their top margins 31 to approximately the points indicated at 33 on Figure 4, and which is at the crotch of the complete garment shown in Figure 1. The lower parts

of said inner curved margins from the points 33 to the bottom edges are, in the finished garment, stitched to the margins 35 of the crotch notch 21 of the front garment portion, the latter seam appearing in front of the garment and being below the garment crotch as shown in Figures 1 and 5. The crotch may be reinforced in the usual or any preferred manner, as shown in Figure 1.

The lower ends of the leg portions of the garment may be finished to suit the taste of the maker. As shown, the inner sides of the legs are closed, and the outer sides 15 may be open downwardly from the points indicated on Figures 2 and 3 at 19, and indicated by the turned-back part 12' of the back portion 12, as shown in Figure 1. If desired, however, the outer sides of the 20 legs may be closed to the bottom edge.

I claim as my invention:

1. The garment described made tubular from end to end and comprising a bust and waist portion, a widened hip portion and 25 leg portions, said garment being made of like shaped back and front portions, the back portion having a deep upwardly opening wide notch extending from the lower margin of said leg portions upwardly to constitute a seat opening and forming at the 30 sides of the notch rear leg portions, and a leg forming and drop seat portion stitched to the inner margins of the back leg portions and to the front garment portion below 35 the crotch and to the back portion outwardly beyond said notch and extending upwardly as a free seat opening closing flap.

2. An under garment comprising two like-shaped front and rear portions to form a tubular waist and bust portion, a lower, wider 40 hip portion and leg portions, the front portion having at its lower margin a shallow crotch notch and the rear portion having a 45 deep notch to form rear leg portions and a seat opening, and a leg forming and drop seat portion stitched at its lower part to the margins of said front and rear notches 50 downwardly below the garment crotch and free above the crotch to constitute a seat opening closing flap.

3. An under garment comprising two like-

shaped front and rear portions to form a tubular waist and bust portion, a lower, wider hip portion and leg portions, the front portion having at its lower margin a shallow 55 crotch notch and the rear portion having a deep notch opening through its lower margin to form rear leg portions and a seat opening, and a seat opening closing flap stitched to the rear garment portion abreast the crotch to form thereabove a seat opening closing flap, and stitched below said crotch to the margins of said notches of the front and rear garment portions to form 60 below the crotch inner closed leg portions. 65

4. An under garment comprising two like-shaped front and rear portions to form a tubular waist and bust portion, a lower, wider hip portion and leg portions, the front portion having at its lower margin a shallow 70 crotch notch and the rear portion having a deep notch to form lateral rear leg portions and an intermediate seat opening, and a seat opening closing flap stitched to the rear garment portion abreast the 75 crotch to form thereabove a seat opening closing flap, and stitched below said crotch to the margins of the front and rear garment portion notches to form at the crotch inner closed leg portions, the side margins 80 of the front and rear garment portions being unattached to each other below a point abreast the crotch.

5. An under garment comprising two like-shaped front and rear portions to form a 85 tubular waist and bust portion, a lower, wider hip portion and leg portions, the front portion having at its lower margin a shallow crotch notch and the rear portion having a deep notch opening through the lower 90 margin thereof to form rear leg portions and a seat opening, and two like-shaped parts having lower leg forming portions stitched at their margins to the margins of the front and rear notches and stitched together at their adjacent side margins from the crotch to the upper end margins thereof to constitute a seat opening closing flap. 95

In witness whereof I claim the foregoing as my invention, I hereunto append my 100 signature this 10 day of February, 1922.

ERWIN G. MUNZER.
